CLAIM

I claim the ornamental design of an electromyography device, as shown and described.

DESCRIPTION

FIG. 1 illustrates a perspective view of an electromyography device;

FIG. 2 illustrates a first face of the electromyography device;

FIG. 3 illustrates a second face of the electromyography device of FIG. 1 that is opposite the first face;

FIG. 4 illustrates a left side view the electromyography device;

FIG. 5 illustrates a right side view of the electromyography device;

FIG. 6 illustrates a top plan view of the electromyography device; and,

FIG. 7 illustrates a bottom plan view of the electromyography device.

The broken lines in the drawings depict portions of the electromyography device that form no part of the claimed design.
